UNITED STATES PATENT OFFICE

118,141

DESIGN FOR A SHOE

Joseph R. Weyand, St. Louis, Mo.

Application October 25, 1939, Serial No. 87,856

Term of patent 3½ years

To all whom it may concern:

Be it known that I, Joseph R. Weyand, a citizen of the United States, residing at the city of St. Louis, State of Missouri, have invented a new, original, and ornamental Design for a Shoe, of which the following is a specification, reference being had to the accompanying drawing forming part thereof.

Fig. 1 is an elevation taken from the outer side of a shoe showing my new design; and

Fig. 2 is an elevation from the inner side of a shoe showing my new design.

The perforations in the quarter extend through the upper, counter and lining.

I claim:

The ornamental design for a shoe, as shown and described.

JOSEPH R. WEYAND.
